2 Sheets-Sheet 2

FIG. 5.

UNITED STATES PATENT OFFICE

WILLIAM M. THEOBALD, OF CLEVELAND, OHIO

APPARATUS FOR CLEANING WINDOW SHADES

Application filed December 20, 1929. Serial No. 415,596.

This invention relates to an improved apparatus for cleaning window shades.

Heretofore, in the cleaning of window shades, it has been necessary after the cleaning operation to re-starch, re-tint, and iron the same. That is, during the previous cleaning operation, the starched condition, as well as the color, has been lost and also there has been experienced a wrinkling and 10 a shrinking as well as a fraying of the shade.

The object of the present invention is to devise an apparatus for cleaning window shades which will obviate the necessity of later re-starching, re-tinting, and ironing the same and which will also prevent any shrinking or fraying of the shade. That is to say, the present invention is contemplated to produce a more efficient manner of cleaning the shade so as to retain the starched and tinted condition of the shade and at the same time, to present the shade in finished condition with a proper gloss upon the one side, and without the shrinking and fraying of the shade.

25 A further object is to devise such an apparatus which may be employed at a considerably reduced cost and which at the same time will produce a much improved result, compared with the old practice, as well as 30 a considerable saving in time.

Other objects will be apparent from the following description and claims when considered together with the accompanying drawings.

35 Fig. 1 is a perspective view of my combined apparatus; Fig. 2 is a sectional view taken on line 2—2 of Fig. 1; Fig. 3 is a sectional view taken on line 3—3 of Fig. 1; Fig. 4 is a sectional view taken on line 4—4 of Fig. 1; and Fig. 5 is a view taken on line 5—5 of Fig. 2.

The present device comprises a table upon which the shade is cleaned and a drying device within which the shade is placed after the cleaning operation. The table may be of various suitable forms of construction and is indicated in a general way by reference numeral 1, while the drying apparatus is indicated in a general way by reference numeral 2. The table is placed with respect to

the drying apparatus so that the shade may be conveniently removed from the table and placed in the drying apparatus, as will be more fully explained.

According to the present invention, the shade or shades are first placed in wet condition upon a suitable sheet of rust-proof metal, as for instance, Monel metal, indicated by reference numeral 3, the shades being indicated by reference numeral 4. 55 The sheet of metal 3 rests upon the table which is provided along its two sides with troughs or drains 5 adapted to receive the cleaning fluid and to deliver the same into a common trough 6 at the end of the table from which it may be discharged through the pipe 7. Any suitable cleaning fluid may be employed with the use of brushes, the shades being first cleaned upon the one side and then upon the other. The metal plate 3 may be kept clean by flushing the same 60 after the successive cleaning operations. The table is provided with an opening extending part way through the middle thereof so as to enable the operator to more readily move the metal plate with the shades thereupon from the table into the drying apparatus, as will more fully appear. It is to be understood that upon completion of 65 the cleaning of the shades, they are smoothed out and retained in smoothed condition upon the plate 3, after the excess cleaning fluid has been removed therefrom, preparatory to their introduction into the drying apparatus. The upper surface of the metal plate 3 is glazed (i. e., glossy or polished) so as to produce the proper degree of gloss upon the surface of the shade which is caused to adhere to the plate, and each plate is provided with a handle 3^a to facilitate the 70 moving of the same into and out of the drying apparatus. The upper surface of the metal plate 3 is glazed (i. e., glossy or polished) so as to produce the proper degree of gloss upon the surface of the shade which is caused to adhere to the plate, and each plate is provided with a handle 3^a to facilitate the 75 moving of the same into and out of the drying apparatus. The upper surface of the metal plate 3 is glazed (i. e., glossy or polished) so as to produce the proper degree of gloss upon the surface of the shade which is caused to adhere to the plate, and each plate is provided with a handle 3^a to facilitate the 80 moving of the same into and out of the drying apparatus. The upper surface of the metal plate 3 is glazed (i. e., glossy or polished) so as to produce the proper degree of gloss upon the surface of the shade which is caused to adhere to the plate, and each plate is provided with a handle 3^a to facilitate the 85 moving of the same into and out of the drying apparatus. The upper surface of the metal plate 3 is glazed (i. e., glossy or polished) so as to produce the proper degree of gloss upon the surface of the shade which is caused to adhere to the plate, and each plate is provided with a handle 3^a to facilitate the 90 moving of the same into and out of the drying apparatus. The upper surface of the metal plate 3 is glazed (i. e., glossy or polished) so as to produce the proper degree of gloss upon the surface of the shade which is caused to adhere to the plate, and each plate is provided with a handle 3^a to facilitate the 95 moving of the same into and out of the drying apparatus. The upper surface of the metal plate 3 is glazed (i. e., glossy or polished) so as to produce the proper degree of gloss upon the surface of the shade which is caused to adhere to the plate, and each plate is provided with a handle 3^a to facilitate the 100 moving of the same into and out of the drying apparatus.

ing bars 3^c of the table may be slightly higher than the side supporting bars 3^d so as to cause the two sides of the plate 3 to slope downwardly and thereby to aid in the draining of the cleaning fluid from the plate into the troughs during the cleaning operation. The plate 3 is of a somewhat flexible nature which will permit the same to maintain such position during the cleaning operation and 10 at the same time will lie perfectly flat while positioned within the drying apparatus so as to insure proper flat condition of the shade when removed therefrom.

The drying apparatus 2 comprises a suitable means for supporting above the floor a number of horizontally disposed steam pipe sections arranged in spaced relation above each other. The steam therefor is supplied from a common source, as indicated by the pipe 8, and individual valves 9 may be provided for each section so as to permit the steam to enter any number of the sections. The drain with valve control is provided upon the other side of the bank 25 of sections, as indicated in a general way at 10. The apparatus 2 includes individual means 11 for supporting the steam sections and also corresponding individual means arranged immediately therebelow, as indicated at 12, for supporting the plates 3. A sufficient number of supporting members are provided so as to maintain the plates in proper flat condition during the drying operation. The drying apparatus 2 may be 30 closed at the top and bottom thereof, as indicated in the drawings, so as to conserve the heat, but it is provided with openings about the sides thereof, as indicated at 13, to afford air circulation and thereby prevent 35 sweating of the shades.

As indicated in the drawings, the level of the cleaning table 1 corresponds substantially with that of the lowermost space of the drying apparatus. As a means of moving the metal plates 3 from the cleaning table to the upper space in the drying apparatus, I have provided the transfer arms 14 fixed upon the rockably mounted shaft 15 45 which can be adjusted by means of the lever connections 16 arranged beneath the table 1. The hand lever 17 is provided with a latch means 18 so that it may be maintained in any position to which it is set for the purpose of inclining the transfer members 14 during the delivery of a plate 3 to a given space of the drying apparatus 2. Upon the adjustable rod 15, there are provided also angle members 19 as a means of 50 guiding the edges of the plate 3 during such transfer thereof to the drying apparatus.

Actual experience with the herein described device has shown that the time required for the drying of a shade is practically ample for the cleaning of a suc-

sive shade. Thus, while the one shade is being dried, another can be cleaned and placed in the drying apparatus, and the first shade can then be removed therefrom and readily stripped from its plate. Any number of spaces can be provided in the drying apparatus so as to accommodate any number of plates at one time. One or more shades can be placed at one time upon each plate, according to the size. If so desired, a table may also be provided upon the opposite side of the drying apparatus, for operation in the same manner. In such case, the drying apparatus would be provided with openings upon the two sides thereof so as to permit the insertion of plates 3 thereinto from either table.

When shades are cleaned and dried in the manner herein set forth, there are realized the advantages above mentioned; that is, they retain their original starch and color, the shade is in a perfectly smooth condition when removed from the plate, and there results a desirable gloss upon the side of the shade which has adhered to the plate during the drying operation, and there is neither shrinking nor fraying of the shade during this manner of treatment. Thus, not only is the present improved method quicker than that heretofore practiced, but there is also realized a considerable saving in time since there is hereby obviated the necessity of re-conditioning the shades after the cleaning and drying. Also, the present improved apparatus is comparatively simple and does not require exceptionally skilled labor in its operation, and each part of the entire operation can be performed without any interference with the other and without any discomfort to the operator.

Other advantages will be obvious to one who is skilled in the art to which the present invention relates.

It is to be understood that the present disclosure is merely for purposes of illustration and can be modified without departing from the spirit of the present invention. All such modifications are intended to be comprehended by the following claims.

What I claim is:

1. Apparatus for cleaning window shades including a polished metallic plate, means for supporting the same, drying means located adjacent said support, and means for supporting the plate for sliding the same from the supporting means to the drying means.

2. Apparatus for cleaning window shades including a polished metallic plate, means for supporting the same, drying means located adjacent said support, said drying means having spaces for receiving the plates at different elevations, means for supporting the plate for sliding the same from the supporting means to the drying means, and

means for varying the degree of inclination of said second mentioned supporting means.

3. Apparatus for cleaning window shades including a polished metallic plate, means for supporting the same, drying means located adjacent said support, said supporting means having a passage-way formed therein and extending in the direction of movement of the plate so as to permit the operator to follow the plate during removal of the same to the drying means.

4. Apparatus for cleaning window shades including a polished metallic plate, means for supporting the same, drying means located adjacent said support, said drying means having a vertical tier of spaces for receiving individual plates, and means for facilitating removal of a plate to a selected space thereof.

20 5. Apparatus for cleaning window shades including a polished metallic plate, means for supporting the same, drying means located adjacent said support, said drying means having a plurality of vertically arranged individual ovens each adapted to receive a plate and heating means therefor, and means for supporting the plate for transferring the same from the supporting means thereto.

30 6. Apparatus for cleaning window shades including a polished metallic plate, means for supporting the same, drying means located adjacent said support, said drying means having a single heating means subdivided into a plurality of individual sections, means for supporting a plate above each of said sections, ventilating means therefor, and means for facilitating placing of the plates in and removing the same from the drying means.

In testimony whereof, I hereby affix my signature.

WILLIAM M. THEOBALD.
